CLAIM

The ornamental design for a double terminal as shown and described.

DESCRIPTION

FIG. 1 is a front perspective view of a double terminal according to the present invention.

FIG. 2 is a rear perspective view of the double terminal of FIG. 1.

FIG. 3 is a front view of the double terminal of FIG. 1.

FIG. 4 is a rear side view of the double terminal of FIG. 1.

FIG. 5 is a right side view of the double terminal of FIG. 1.

FIG. 6 is a left side view of the double terminal of FIG. 1.

FIG. 7 is a top view of the double terminal of FIG. 1.

FIG. 8 is a bottom view of the double terminal of FIG. 1.

FIG. 9 is a front perspective view of a double terminal according to the present invention.

FIG. 10 is a front view of the double terminal of FIG. 9.

FIG. 11 is a rear side view of the double terminal of FIG. 9.

FIG. 12 is a right side view of the double terminal of FIG. 9.

FIG. 13 is a left side view of the double terminal of FIG. 9.

FIG. 14 is a top view of the double terminal of FIG. 9; and,

FIG. 15 is a bottom view of the double terminal of FIG. 9.

The dashed lines illustrate environment that does not form a part of the present invention, and no claim is made to the material illustrated with dashed lines.

1 Claim, 15 Drawing Sheets
